UNITED STATES PATENT OFFICE

162,598

LADY'S STOCKING

Willy M. Vogler, Shillington, Pa.

Application July 3, 1950, Serial No. 10,935

Term of patent 7 years

(Cl. D47—7)

To all whom it may concern:

Be it known that I, Willy M. Vogler, a citizen of the United States, residing at Shillington, in the county of Berks and State of Pennsylvania, have invented a new, original, and ornamental Design for a Lady's Stocking, of which the following is a specification, reference being had to the accompanying drawing, forming part thereof.

I claim:

The ornamental design for a lady's stocking, as shown.

WILLY M. VOGLER.
